UNITED STATES PATENT OFFICE.

JOSEPH H. POPE, OF HAMILTON, MASSACHUSETTS, ASSIGNOR TO UNITED SHOE MACHINERY CORPORATION, OF PATERSON, NEW JERSEY, A CORPORATION OF NEW JERSEY.

METHOD OF MAKING SHOES.

1,386,654.

Specification of Letters Patent. Patented Aug. 9, 1921.

Application filed September 8, 1919. Serial No. 322,524.

To all whom it may concern:

Be it known that I, JOSEPH H. POPE, a citizen of the United States, residing at Hamilton, in the county of Essex and State 5 of Massachusetts, have invented certain Improvements in Methods of Making Shoes, of which the following description, in connection with the accompanying drawings, is a specification, like reference characters on 10 the drawings indicating like parts in the several figures.

This invention relates to methods of making shoes and is herein described and illustrated in its application to the manufacture 15 of shoes of the type commonly known as moccasins, a moccasin of the type illustrated being a foot covering of which the sole, the sides and the toe and heel portions are formed from a single piece of material and 20 which is completed by securing to the margin of the fore part an upper piece to form a covering for the toe and instep, a further piece being sometimes added to form a top which may be laced about the ankle. Shoes 25 of this general type have been long used by woodsmen and hunters, but because of the hand work required they have been relatively expensive and have been so lacking in shapeliness and wearing qualities as to limit 30 greatly the demand therefor. An object of this invention is to provide a method by which shapely and durable shoes of this kind may be made with a minimum of manual labor.

35 A further object of the invention is to improve the method disclosed and claimed in Letters Patent of the United States No. 1,381,921 granted June 21, 1921, on application of John J. Heys, without sacrifice of 40 its utility.

The present invention, while preserving the many important advantages and essential steps of the method disclosed in said patent, presents various practical advantages thereover, particularly with relation 45 to the steps of molding the material into final shape.

In the practice of the method set forth in the above-identified patent, the final 50 molding operation is effected between a rigid inner form and a contractible rigid outer form or partible mold the parts of which move in predetermined paths. There is, therefore, no conformation of the molding surfaces to the thickness of the leather 55

and no adaptation of one molding surface to the contour of the other. Moreover, in such rigid molds there must be joints between the mold parts which may make marks or blemishes on the molded article where the 60 joints occur; in fact, severe injury to the stock may result from closing such a mold upon it.

In one important aspect this invention insures obtaining uniform molding action on 65 all parts of the moccasin being molded, whatever the thickness or textural characteristics of the stock, while preserving all the advantages of the use of forms or molds as described in said patent.

70 A distinguishing characteristic of the present method consists in applying to a blank, prepared as to its first stages in accordance with the method set forth in the Heys patent, a substantially uniform pressure 75 to mold it into final shape. As herein shown a rigid inner mold, which may be a last, is used and the blank, after having been given a preliminary vessel or pouch shape, is placed over the form and uniform pressure 80 is applied thereto externally. This is effected preferably by forcing the inner form and blank sole down against a yielding and preferably elastic diaphragm beneath which a fluid under pressure, preferably a liquid, may be admitted. While the pressure is continued fluid pressure from beneath is applied which, of course, is equal in all directions and causes the diaphragm 85 to wrap about the form and force all portions of the blank into contact with the form.

90 Another distinguishing characteristic of the method consists in confining the margin of the molded blank to the inner mold or die. Preferably this is effected by drawing loops of a filament in opposite directions, one loop passing about the toe end of the blank near its edge and the other loop passing about the heel end of the blank. By 100 this method the blank is drawn tightly against the upper receding portions of the form. Preferably above the said portion is an outwardly flaring portion, the loops acting to force the upper into the angle between these portions. To hold the blank in this position a draw string may be arranged in the margin of the blank before it is molded and tightened after the molding operation, as described, has taken place. If de- 105 110

sired, in place of the draw string a string or wire may be passed tightly around the molded blank in the vicinity of the loops and fastened to hold the blank.

5 A further characteristic of the method consists in separating the form or last in a plane just above the draw string or binding wire and in trimming off the excess of material about the periphery of the blank while 10 using the flat top of the form as a guide to determine the trimming line.

A still further characteristic of the method consists in applying to the top face of the last in place of the removed portion 15 a block of a shape to complete the last. The other parts needed to complete the moccasin are then placed upon the last, secured in assembled relation thereon and their lower edges sewed to the trimmed upper edge of 20 the blank formed on the last, the seam being preferably made by a machine.

The present method is herein set forth for the purpose of illustration but not by way of limitation as practised by the use of apparatus embodying novel features characteristic of the apparatus shown and claimed 25 in copending application Serial No. 287,516, filed April 4, 1919, in the name of Louis A. Casgrain.

30 These and other characteristics of this novel method will appear more fully from the following description when read in connection with the accompanying drawing and will be pointed out in the appended claims.

35 In the drawing:

Figure 1 is a view of the blank to be molded, the blank having a draw string run into its margin;

40 Fig. 2 is a sectional view showing the blank undergoing the preliminary molding or breaking-down operation;

Fig. 2^a is a perspective of the blank formed by the apparatus of Fig. 2;

45 Fig. 3 is a sectional view showing a preliminarily formed blank placed over a last-shaped form and located over an elastic diaphragm;

50 Fig. 4 is a similar sectional view showing the form or last being forced against the diaphragm to press the sole portion of the blank against the bottom of the last;

Fig. 5 is a similar sectional view showing the blank held in molded position against the last;

55 Fig. 6 is a perspective view showing the manner of drawing in the margin of the blank and securing it;

Fig. 7 is a perspective view showing the last with the top portion removed and the 60 blank held in molded position;

Fig. 8 is a side elevation, partly in section, showing the excess of material at the margin of the blank being trimmed away;

65 Fig. 9 is a view similar to Fig. 8 showing the part of the last on which the molding

is done with the top portion secured thereto to complete the last; and

Fig. 10 is a similar view showing the top and toe portions of the shoe applied to the last and sewed to the molded bottom and side portions by a single continuous seam.

In the practice of the method of this invention a blank *a* is prepared of the shape shown in Fig. 1. Through the margin of this blank a draw string *b* may be run as 75 shown. The blank *a* is then given a preliminary vessel or pouch shape, as shown in Fig. 2, the blank being laid over an opening 2 in a table 4, its marginal portions being confined by a yielding pressure plate 6 and 80 its central portion being pressed through the opening 2 by a descending plunger 8. The blank is thus formed into a narrow vessel or pouch having approximately the length of the shoe to be formed and a portion thereof given approximately the peripheral length 85 which it is to have in the finished shoe. The vessel blank designated as *a*¹ is then placed over a last or form 10 having the shape of the bottom, side and end portions of the 90 shoe to be made.

The top of the last 10 is flat and there is secured to its top a piece 14 which has the contour of the top of the last and has an outwardly flaring edge face 16. The blank *a*¹ is then assembled on the last 10, 14 and 95 placed on a rubber diaphragm 18 which is confined at its margin to the rim 20 of a

tank 22 into which a liquid may be admitted under pressure through a pipe 24. The tank 100 and last are then moved relatively to the position shown in Fig. 4, the rubber diaphragm stretching and smoothing out the material covering the last bottom. This movement may be effected by pressing upon 105 the last a foot piece 26 actuated from any suitable source of power. Liquid under pressure is admitted to the tank 22, causing the diaphragm 18 to assume the form shown in Fig. 5 and to wrap the side and end portions 110 of the blank about the last 10 and press them against the sides and ends of the last. The margin of the molded upper is then subjected to the action of wire loops 30, 32 (Fig. 6) which are drawn against the end 115 portions of the blank from opposite directions. As shown, the ends of the loops are held clamped in cross pieces 34, 35 and are moved in opposite directions by turning thumb nuts 36, 37 on threaded rods 38, 39 connected to the cross pieces 34, 35 and passing through holes in brackets 40, 41 connected to the tank 22. The margin of the blank having been drawn in against the receding upper portion of the last 10 and into 120 the angle between that portion and the outwardly flaring face 16, the draw string *b* is drawn up tight and fastened. If desired, 125 in place of the draw string, a cord or wire may be passed around the form at this 130

time in the vicinity of the loops 30, 32, drawn tight and fastened. The loops 30, 32 are now loosened, the liquid pressure in the tank relieved by operating the three-way cock 33, the last removed, and the two parts 10, 14 separated. The blank in the form which it has now been made to assume is designated as a^2 in Fig. 7.

The margin of the blank a^2 is necessarily more or less irregular and the next operation consists in trimming off the excess of material about the periphery of the blank. This is preferably done by employing the flat top of the form 10 as a guide for a trimming knife by which the margin is removed, preferably at a slight but uniform distance above the plane of the top of the form 10. The blank thus trimmed is shown at the right of Fig. 8 and designated as a^3 . A top portion 50 is now secured to the top face of the form 10 to form the upper portion of a complete last. The other portions of the shoe, for example, the toe portion c and the top portion d , are assembled on the last with their lower edges in proper relation to the top edge of the blank a^3 and are secured to the last temporarily by any suitable means. The meeting edges of the parts a^3 , c , and d are then united by a single continuous seam e which is preferably sewed on a machine.

Having thus described my invention, what I claim as new and desire to secure by Letters Patent of the United States is:

35. 1. That improvement in the art of making shoes which comprises molding a substantially flat blank to produce a blank having smooth unwrinkled sides upstanding from the central portion, and then subjecting substantially all portions of the blank thus formed to equal molding pressure to cause them to assume the contour of the bottom and sides of a finished shoe part.

2. That improvement in the art of making shoes which comprises forcing a substantially flat blank through an opening of less area than the bottom of the shoe to produce a blank having substantially straight sides upstanding from the central portion, and then subjecting the blank thus formed to uniform molding pressure to cause the sides to assume the contour of a finished shoe part.

3. That improvement in the art of making shoes which comprises confining the marginal portion of a substantially flat blank, effecting relative movement of the confined and the unconfined portions in a direction transverse to the plane of said confined portion to shape the blank with upturned sides, permitting the marginal portion of the blank to be withdrawn from its confined position by such relative movement and to assume upturned relation to the central portion of the blank, opposing to one face of

the blank a rigid die having the contour which it is desired the molded blank shall assume, and then subjecting all portions of the other face of the blank to substantially equal pressure.

4. The method of making shoes which comprises preliminarily molding a blank to cause it to assume the shape of a vessel or pouch having a smaller dimension than the corresponding dimension of the completed shoe, opposing to one face of the blank a die having the contour to which it is desired to mold the blank, and subjecting the opposite face of the blank to substantially equal pressure to cause it to assume the shape of the die.

5. That improvement in the art of making shoes which comprises preliminarily molding a blank to cause it to assume an elongated vessel shape of smaller dimensions than those of the completed article to be formed therefrom, placing the blank upon a last-shaped form, and then subjecting the exterior of the blank to substantially uniform pressure.

6. That improvement in the art of making shoes which comprises molding a substantially flat blank to produce a blank having smooth unwrinkled sides upstanding from the central portion, and subjecting both faces of the blank to molding pressure between continuous surfaces.

7. That improvement in the art of making shoes which comprises forcing a substantially flat blank through an opening of less area than the bottom of the shoe to produce a blank having substantially straight sides upstanding from the central portion, and then subjecting one face of the blank to molding pressure applied through a yielding medium while supporting the opposite face of the blank rigidly.

8. That improvement in the art of making shoes which consists in subjecting a blank to a breaking down operation to reduce the peripheral extent of the blank without the formation of wrinkles, then subjecting the blank thus formed, no part of which has its final form, to further shaping operations to produce a shoe part comprising a sole, side and end portions of the contour of a finished shoe, said operations including the application of substantially uniform pressure to one surface of the side and end portions of the blank while opposing to the other face a rigid shoe-shaped form.

9. That improvement in the art of making shoes which comprises first molding a blank into a shape approximating that of the desired shoe part, opposing to all portions of one surface of the blank except its marginal portion a rigid form to which the blank is to be molded, subjecting the other face of the blank to uniform pressure to cause it to assume the shape of the form, binding the

marginal portion of the blank to prevent substantial change of form of the blank when the molding pressure is relieved, and then removing the molding pressure.

- 5 10. That improvement in the art of making shoes which consists in subjecting a blank to a breaking down operation to reduce the peripheral extent of the blank without the formation of wrinkles, then subjecting the blank thus formed, no part of which has its final form, to further shaping operations to produce a shoe part comprising a sole, side and end portions of the contour of a finished shoe, said operations including the application of substantially uniform pressure to one surface of the blank
- 10 15. 11. That improvement in the art of making shoes which comprises preparing a form having the shape of the bottom, sides and ends of a shoe and an outwardly and upwardly flaring face above the sides, molding a blank to the form, securing the blank in molded position by a binding filament arranged below said flaring face, removing the flaring face, trimming away the marginal portion of the blank thus exposed, placing on the form a top portion corresponding to the shape of the last, placing upon the top portion the parts of the shoe required to finish the shoe, and attaching said parts to the molded blank by a seam.
- 20 25. 30. 35. 40. 12. That improvement in the art of making shoes which comprises preparing a form having the shape of the bottom, sides and ends of a shoe and having a flat top, attaching to the top a member having an outwardly and upwardly flaring face, molding a blank to the form, securing the blank in molded position by a binding filament arranged adjacent to the flat top of the form, removing the top part of the form, trimming away the marginal portion of the blank thus exposed while employing the top

face of the form as a guide, replacing the removed portion by a top portion corresponding to the shape of the last, placing upon the top portion the parts of the shoe required to finish the shoe, and attaching said parts to the molded blank by a seam.

13. That improvement in the art of making shoes which comprises preparing a form having top and bottom parts, the bottom part having substantially the shape of a last and the top part having a shape different from the top portion of a last, shaping a blank to the bottom portion of the last, binding the blank to the form along lines adjacent to the line of separation of the top and bottom parts, removing the top part, trimming the margin of the blank, replacing the top part by a part having a shape to constitute, with the bottom part, the shape of a complete last, assembling on the last shoe parts necessary to complete the shoe, and uniting by a seam said parts to the blank shaped on the bottom part.

14. That improvement in the art of making shoes which comprises preparing a form having the shape of the bottom, sides and ends of a shoe and having a removable top portion, molding a blank to the form, binding the blank to the form along a line adjacent to the line of separation of the form, removing the top portion of the form, trimming the edge of the blank to a contour corresponding to that of the top of the bottom portion of the form, replacing the top portion by a top portion having the shape of the top portion of a last, placing upon the top portion the parts of the shoe required to complete the shoe, and attaching said parts to the molded blank by a seam.

In testimony whereof I have signed my name to this specification.

JOSEPH H. POPE.
